E. KOERNER

CUT-OFF KNIFE FOR CIGARETTE MACHINES

Filed August 26, 1925

The diagram illustrates a circular device, possibly a reel or a drum, with various internal and external components labeled. The top part shows a cross-section with a central circular area labeled 5, which is shaded. Surrounding this are several concentric layers and lines labeled 1, 2, 3, 4, and 6a. A small circle labeled R is located in the upper right corner. The bottom part shows a similar cross-section with a central area labeled 6a, also shaded, and surrounding layers labeled 1, 2, and 4. The label 'Fig. 1' is positioned in the upper left corner of the drawing.

INVENTOR

E. WALDHOERNER

BY

J. Granville Meyers.
ATTORNEY

UNITED STATES PATENT OFFICE.

EWALD KOERNER, OF DRESDEN, GERMANY, ASSIGNOR TO UNITED CIGARETTE MACHINE CO., INC., OF LYNCHBURG, VIRGINIA, A CORPORATION OF VIRGINIA.

CUT-OFF KNIFE FOR CIGARETTE MACHINES.

Application filed August 26, 1925. Serial No. 52,537.

To all whom it may concern:

Be it known that I, EWALD KOERNER, a citizen of the Republic of Germany, and resident of Dresden, Germany, have invented 5 certain new and useful Improvements in Cut-Off Knives for Cigarette Machines, of which the following is a specification.

My invention relates to cut off knives or blades to be used in cigarette machines and 10 for analogous purposes.

The objects of the invention are to provide a very thin knife or blade which will cut a continuous cigarette rod or cigarette mouth piece without distorting or bending 15 the rod, or its paper cover or the mouth piece at the point of cutting; to provide such a blade with a substantially eccentric cutting edge which provides a shearing cut, and also to provide the blade with a slot 20 arranged for easy mounting and adjusting of the blade in relation to a rotary shaft and between shaft flanges which clamp the blade in position.

Cut off knives or blades for analogous 25 purposes have heretofore been made of relatively thick material, such as cast steel, and on account of their thickness substantially deform or bend the cigarette rod or the cover paper, or the mouth piece adjacent the cutting point. The provision of a thin blade, which may be produced from thin sheet or strip steel prevents such distortion of the product. While the invention is not limited 30 as to the exact thickness of the blade, the blades are made very much thinner than has been customary in this art. They may be as thick as ordinary cardboard or in some cases substantially of the thickness of an ordinary safety razor blade. It has also been custom- 35 ary heretofore to make cut off knives of circular form, requiring movement of the knife in its own plane to cut the rod or mouth piece. The provision of a substan- 40 tially eccentric cutting edge avoids in some cases the necessity for any movement of the knife in its own plane; or if such movement is provided it may be materially reduced and in any case the eccentric edge provides a more effective shearing cut than is obtained 45 with a circular knife. The mounting and adjusting slot is cut in the blade from a point substantially opposite the cutting edge to substantially the normal or original cen-

ter of the blade. This slot may be passed over the blade shaft as the blade is inserted 55 between clamping discs or flanges, and as the blade is ground down and worn away at the cutting edge it may be easily and quickly moved out and reclamped.

The described features, and especially the 60 eccentric cutting edge also permits or facilitates grinding the edge while the knife remains in position in the machine, without removing it for grinding, as is necessary in many cases with blades heretofore used. 65

The characteristics and advantages of the invention are further sufficiently explained in connection with the following detailed description of the accompanying drawing, which shows one exemplifying embodiment 70 of the invention. After considering this embodiment, skilled persons will understand that many variations may be made within the principles of the invention, and I contemplate the employment of any structures 75 that are properly within the scope of the appended claims.

Fig. 1 is a side elevation of a blade or knife embodying the invention in one form, with certain parts of its support or mounting sufficiently indicated in a diagrammatic way.

Fig. 2 is a plan view with the rotary mounting or blade support sufficiently indicated in simplified form.

The knife or blade B is stamped or otherwise formed from sheet or strip steel of suitable composition and hardness, and of thin section, as sufficiently indicated in Fig. 2. When cut from a strip of suitable width, 90 certain limits of the blade are defined by parallel edges 1, which are the edges of the original strip. One other portion of the blade may have a substantially circular outline as at 2. Substantially opposite this 95 curved or circular contour is the cutting edge 3 which is curved or usually arcuate and eccentric to the approximate center of the blade, or as otherwise described, the curved edge 3 may be defined by a radius 100 centered elsewhere than on an imaginary median parallel of the two parallel edges 1.

The cutting edge may be produced by grinding to a simple bevel, as shown in Fig. 2, or otherwise in some cases, the edge 105 may be double beveled.

A slot 4 is provided, usually running from the curved "back" edge 2 to the normal or original center of the blade.

The blade is mounted by passing the slot 5 over a shaft 5 as the blade is inserted between clamping flanges 6. The position of the flange outline in relation to the blade in one of its adjusted positions is indicated by the dot-and-dash line 6^a in Fig. 1. 10 When so mounted the arcuate cutting edge 3 is evidently eccentric to the shaft center and therefore will produce a shearing cut with or without a lateral movement of the shaft when the blade is rotated in the direction of the arrow. This is sufficiently explained by the relative position of the cigarette rod R in Fig. 1, which otherwise might be a tubular cardboard mouth piece of a Russian type cigarette. The cutting edge may be 20 sharpened from time to time while it is in working position, by bringing it in contact with a suitable grinder which may be arranged as part of or as an attachment to the cigarette machine. As the edge wears away 25 the blade may be readjusted in an obvious manner by loosening the clamping flanges

6, moving the cutting edge outward or to the right, in the position shown in Fig. 1, and retightening the flanges 6.

I claim:—

1. A cut-off knife for cigarette machines and similar purposes, comprising a thin metal blade having an eccentric cutting edge, and also having a slot extending from approximately the normal center of the blade 35 to an edge substantially opposite the cutting edge.

2. A cutter for purposes set forth formed from a strip of thin sheet steel and having parallel edges, an arcuate cutting edge joining the parallel edges and generated on a radius centered away from the median parallel of said parallel edges, the blade also having a slot extending from the normal blade center to a blade edge substantially opposite the cutting edge, the slot being substantially parallel to said parallel blade edges.

Signed at Dresden, Germany, this 8th day of August A. D. 1925.

EWALD KOERNER.
